MOBILE DOUBLE DIAPHRAGM PUMP OR THE LIKE

James A. Mixon, 4063 Salisbury Road,
Jacksonville, Fla. 32216

Filed July 13, 1971, Ser. No. 162,319

Term of patent 14 years

Int. Cl. D15—02

U.S. Cl. D65—1 A

FIG.1

FIG. 2

FIG.3

FIG.4

FIG.5

FIG.6

FIG. 1 is a top plan view of my mobile double diaphragm pump or the like in accord with my new design; FIG. 2 is a bottom view thereof; FIG. 3 is a front end elevational view thereof; FIG. 4 is a rear end elevational view thereof; FIG. 5 is a right side elevational view thereof; and FIG. 6 is a sectional view taken along line 6-6 of FIG. 4.

Portions of FIGS. 5 and 6 have been broken away for convenience of illustration.

I claim:
The ornamental design for a mobile double diaphragm pump or the like, substantially as shown.
